[57] CLAIM

The ornamental design for a concrete trash container, as shown and described.

DESCRIPTION

FIG. 1 is a front elevational view showing my new design, the rear elevational view being a mirror image thereof.

FIG. 2 is a side elevational view thereof, the opposite side view being identical.

FIG. 3 is a front perspective view of the design.

FIG. 4 is a sectional view thereof, taken along line 4—4 of FIG. 1.

The bottom of the trash container is substantially planar and unornamented.
